INVENTOR

William L. Lee

BY

Nathan D. Leonard

ATTORNEY.

UNITED STATES PATENT OFFICE.

WILLIAM L. LEE, OF HELENA, MONTANA.

PAPER-HOLDER.

1,310,242.

Specification of Letters Patent. Patented July 15, 1919.

Application filed April 11, 1919. Serial No. 289,355.

To all whom it may concern:

Be it known that I, WILLIAM L. LEE, a citizen of the United States, residing at Helena, in the county of Lewis and Clark, 5 State of Montana, have invented certain new and useful Improvements in Paper-Holders; and I do declare the following to be a full, clear, and exact description of the invention, such as will enable others skilled 10 in the art to which it pertains to make and use the same.

My invention relates to an improvement in paper holders and more particularly to a holder for rolls of toilet paper.

15 The object of the invention is to provide a holder which will retain the roll of toilet paper securely in place and yet allow the same to revolve freely as the paper is withdrawn, and also allow of the roll of paper 20 being readily removed and another roll substituted therefor when desired.

A further object is to provide a holder which will allow the roll of paper to revolve freely and at the same time prevent the dis- 25 lodgment of the same.

A further object is to provide a holder with means for holding a roller or core, adapted to support a roll of toilet paper, and also with means for preventing the endwise 30 movement of the roller or core.

A further object is to provide a holder which may be easily attached to the wall, or other support, and which is held steady by the weight of the roll of paper and its own 35 weight against the wall which acts as a brake and offers sufficient resistance to keep the paper from unrolling too fast.

A still further object is to provide a holder which is simple, inexpensive and durable in construction and efficient and convenient in use.

Referring to the drawings:—

Figure 1 is a top plan view with a roll of toilet paper shown therein.

45 Fig. 2 is a front view with a roll of toilet paper shown in dotted lines.

Fig. 3 is a side view with a roll of paper shown in dotted lines.

In the drawings in which similar reference 50 characters denote similar parts throughout the several views, 1 represents the frame of

the holder, which is preferably made of wire but which may be made of any other suitable material, formed of a single piece of wire which is bent to form the several parts of 55 the device.

The frame comprises two arms 2 and 3 each of which is inclined as at 4 from a central point 5 which point is adapted for the reception of a screw or nail or other device 60 for attaching the frame to a wall or other support. From the point 6 where the outwardly inclined portions of the arms terminate each arm extends vertically downward as at 7 and its lower end is bent upwardly 65 forming a hook 8, curved laterally as at 9 and terminated in a downwardly and rearwardly inclined portion 10, the extreme end of which is in approximate alinement with the vertical portions of the arms. 70

A roller or core 11 is provided on which the roll of toilet paper 12 is mounted, the end portions of the roller being mounted freely in the hooked portions 8 and being retained in place and prevented from endwise 75 or lateral movement by means of the downwardly and rearwardly inclined portion 10 against which the extreme ends of the roller are adapted to abut.

I do not wish to be understood as limiting myself to the specific details of construction and arrangement as herein described and illustrated, as it is manifest that variations and modifications may be made in the features of construction and 85 arrangement, in the adaptation of the device to various conditions of use, without departing from the spirit and scope of my invention and improvements. I therefore reserve the right to all such variations and 90 modifications as properly fall within the scope of my invention and the terms of the following claims.

What I claim is:—

1. A holder for a roll of toilet paper, comprising a roller, a frame having arms inclined downward from a central point, then extending vertically and approximately parallel, their lower portions bent upward to form hooks in which the roller is adapted 95 to be mounted, then curved laterally outward and finally downward at an angle 100

forming an abutment for the ends of the said roller.

2. A holder for a roll of toilet paper, comprising a roller, a frame having arms inclined downward from a central point, then extending vertically downward and each

formed into a hook then curved laterally outward and finally inclined downward at an angle, said inclined portion forming an abutment for the ends of the said roller.

10

In testimony whereof I affix my signature.

WILLIAM L. LEE.
